ATTORNEY

UNITED STATES PATENT OFFICE.

LEO B. PREISSNER, OF HARTFORD, CONNECTICUT.

CARPENTER'S CHALK-LINE.

1,274,776.

Specification of Letters Patent.

Patented Aug. 6, 1918.

Application filed June 29, 1917. Serial No. 177,750.

To all whom it may concern:

Be it known that I, LEO B. PREISSNER, a citizen of the United States, residing at Hartford, in the county of Hartford and 5 State of Connecticut, have invented certain new and useful Improvements in Carpenters' Chalk-Lines, of which the following is a specification.

This invention relates to certain new and 10 useful improvements in reels, and more particularly in a reel of the chalk line type.

The primary object of the invention is to provide a reel with means for clamping the loose end of the line wound thereupon, 15 whereby the line may be held from further winding or unwinding movement at any suitable point, thus doing away with the necessity of knotting the line about the spool or reel after using the same.

20 Another object of the invention is to provide a line holding attachment which can be readily attached to any standard type of reel, only slight modification of the latter being rendered necessary, thus providing a 25 useful commodity which can be manufactured and sold at a reasonable cost.

The above and other objects and advantages of this invention will be in part described and in part understood from the 30 following description of the present preferred embodiment, the same being illustrated in the accompanying drawings, in which,

Figure 1 is a side view of my invention. 35 Fig. 2 is an end view of the same.

Fig. 3 is a view similar to Fig. 2, but looking in the opposite direction and,

Fig. 4 is a longitudinal sectional view.

In the drawings wherein is illustrated the 40 preferred form of my invention, the numeral 1 indicates a drum which is provided with the usual side flanges 2 and 3. The side flange 2 is provided with a radial slit 4 extending inwardly from its periphery 45 toward the center thereof and adapted for a purpose to be hereinafter set forth. Extending longitudinally through the drum 1 is a passageway 5, enlarged at one end to provide a recess 6. A plate 7 is secured to 50 the recessed end of the drum 1 and is equipped with a small opening 8, communicating with the recess 6. Slidably mounted in the passageway 5 is a rod 9 provided at one end with an enlarged head 10, said head 55 10 being slidably mounted in the recess 6

and equipped with a reduced extension 11 adapted to project through the opening 8 in the plate 7 to provide a thumb button. Positioned in the recess 6 and surrounding the rod 9 is a coiled compression spring 12 60 having one end thereof bearing against a shoulder 13 and the opposite end engaging the head 10. The opposite end of the rod is bent at right angle to provide a hook 14 which is normally held against the flange 2 65 by means of the spring 12.

In the practical use of my device the hook 14 is normally held against the flange 2, owing to the pressure exerted against the head 10 by the compression spring 12. 15 70 16 indicates a line wound upon the drum and the loose end thereof. When it is desired to secure the line from unwinding the loose end 16 is passed through the slit 4, then by pressing the extension 11 with the 75 thumb, the rod 9 will be moved to space the hook 14 from the flange 2, and the loose end of the line is then inserted beneath the hook and is thereby clamped against the flange 2.

What I claim is:—

1. A reel, including a drum provided with a longitudinal bore enlarged at one end to form a recess, a rod slidably mounted in said bore, a hook formed on one end of said rod, a spring positioned in said recess and 85 surrounding said rod, an enlarged head formed on the opposite end of said rod and engaging said spring, a reduced extension formed on said head and a perforated plate secured to the recessed end of said drum and 90 surrounding said extension.

2. A device of the character described including a flanged drum having a central longitudinal passage and one flange slotted, a chalk line wound around the drum with one 95 end inserted in the slot, a rod movable longitudinally in the passage, an extension projecting laterally from one end of the rod to engage the line between it and the adjacent flange, an extension on the other end of the 100 rod projecting from the drum for engagement by the finger, and resilient means urging the rod in a direction to retain the grasp upon the line.

In testimony whereof I affix my signature 105 in presence of two witnesses.

LEO B. PREISSNER.
